UNITED STATES PATENT OFFICE.

GEORGE WILBUR SHIPLEY, OF HARMANS, MARYLAND.

WINDOW-SCREEN ATTACHMENT.

1,186,139.

Specification of Letters Patent. Patented June 6, 1916.

Application filed August 11, 1914. Serial No. 856,283.

To all whom it may concern:

Be it known that I, GEORGE WILBUR SHIPLEY, citizen of the United States, residing at Harmans, in the county of Anne Arundel and State of Maryland, have invented certain new and useful Improvements in Window-Screen Attachments, of which the following is a specification.

My invention relates to window screen attachments, and as its primary object contemplates improved adjustable means operable to provide for lateral increase or decrease in the size of a standard screen.

The invention, as a further object, aims to provide a window screen attachment comprising a pair of attachment sections, one of the said sections being movable laterally of the screen relatively to the other section; spring means being interposed between said sections, said means normally holding the movable section in its outermost position, and, when fitted within a window frame holding the screen sides between the guide strips of the frame.

As a still further object, I provide simple and efficient means whereby the movable attachment section may be locked against lateral play or movement after having been adjusted as desired.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like corresponding parts throughout the several views, and in which:—

Figure 1 is a front elevation of a window frame, a screen having my improved attachment associated therewith being shown; Fig. 2 is a section on the line 2—2 of Fig. 1; Fig. 3 is an enlarged fragmentary longitudinal sectional view of the attachment, a portion of the immovable attachment section being shown in elevation; Fig. 4 is a view similar to Fig. 1, a modified form of attachment being shown; Fig. 5 is a section on the line 5—5 of Fig. 4; Fig. 6 is a fragmentary longitudinal sectional view of the attachment shown in Fig. 4; Fig. 7 is a view simi-

lar to Fig. 2 illustrating a modified form of lock means; and Fig. 8 is a fragmentary view illustrating the lock means in elevation.

Before proceeding with the description of the drawings, I desire to call particular attention to the fact that while I have evolved and shown my invention with reference to its application as an accessory to wood-frame screens, the same may be readily utilized, by slightly modifying the form of the immovable attachment section as an accessory to metal-frame screens.

Referring now to the drawings by numerals, 1 designates as an entirety the window frame, 2 the lower window sash, 3 the upper window sash, and 4 an ordinary wood-frame screen, one of the lateral edges of the said screen fitting between the guide strips of the frame as shown. Upon the opposite edge of the said screen 4 is attached, as indicated at 5, the immovable attachment section 6, comprising a part of the screen attachment designated as an entirety by the numeral 7. As illustrated to advantage in the sectional view, Fig. 2, the immovable section 6 is composed of a single elongated strip of metal bent equi-distant its respective longitudinal edges to form a socket 8 within which the opposite lateral edge of the screen 4 is fitted, the fastening means shown at 5 serving to hold the screen in place. Adjacent the respective longitudinal edges of the plate or strip from which the immovable screen attachment section is formed, the said strip is bent inwardly as indicated at 9 to form, between the respective edges of the strip, a longitudinally extending slot 10, the latter serving as a guide for and receiving the movable attachment section designated as an entirety by the numeral 11. Said movable attachment section 11 is also composed of a single strip of elongated metal bent upon itself as shown to form enlargements designated respectively 12 and 13, the enlargement 12 operating within the space or casing formed by the bending of the metal strip of which immovable section 6 is composed, a leaf spring 14 (or a plurality, if necessary), being engageable with the inner face of the enlargement 12 to normally hold said movable section 11 in its normal position or, when the screen is arranged within the window frame, holding the enlargement 13 in proper place.

between the guide strips of the frame, the holding being yieldable in its nature. Leaf spring 14 is arched as shown to advantage in Fig. 3, it being attached intermediate its ends as indicated at 15' to the enlargement 12, the terminals of the spring abutting or engaging that portion of the strip, from which the immovable section 6 is formed, defining socket 8.

10 As a means whereby movable section 11 may be locked, subsequent to lateral adjustment, I provide a bracket 15 so shaped or formed as to partially embrace, not only enlargement 12, but the spring 14, the engagement between the said bracket and the said enlargement serving as a means whereby the former is held in place. An extension 16, forming a part of the bracket, extends inwardly, or away from the screen, 20 said extension carrying a fastening screw 17, so disposed relatively to immovable section 6 as to extend through a slot 18 formed therein, the slot being of a length sufficient to provide for lateral movement of the 25 bracket and screw in an adjusting operation, and, as shown to advantage in Fig. 1, extending transversely of the section within which it is formed. A thumb nut 19 is adjustable upon the screw 17, the nut being 30 engageable with the outer face of section 6 to provide, when tightened, a means whereby said movable section 11 is locked or fastened immovable relatively to the section 6.

35 In the modified form shown in Figs. 4, 5 and 6, the construction of the attachment is substantially the same as in the preferred form, the enlargement 20 of movable section 21, being somewhat increased in size to provide for its engagement, throughout its 40 length, with the inner wall of the casing forming immovable section 22, the contacting point being shown at 23. The fastening means is dispensed with, the spring 24 alone 45 serving to hold section 21 in proper place relatively to the section 22.

Passing on now to a detail description of the modified lock means, illustrated in Figs. 7 and 8, 25 designates the immovable attachment section and 26 the movable attachment section, the latter extending into the former in a manner much the same as that described in the preferred form. Said movable section 26 is enlarged as at 27, the enlargement having a spring 28 affixed thereto. Immovable section 25 is horizontally slotted as at 29, through which slot an attaching bolt 30 extends, the bolt being in turn slit or slotted as at 31, the slit being of a size 60 to receive the enlarged portion of the movable section 26 and the adjacent portion of the spring 28, an opening (not shown) being formed in the said movable section through which a portion of the attaching bolt 30 extends. A nut 32 is threaded on

70 bolt 30, the nut being slit or grooved to receive a portion of the enlargement 27, the groove of the nut and the slot of the bolt being aligned. As shown, nut 32 is engageable with the inner face of the slotted portion of stationary section 25. Bolt 30 is threaded throughout the greater portion of its length, the threaded portion extending through the said slot 29 and having mounted thereon a washer 33 and a thumb nut 34 the 75 latter being adjustable relatively to the nut 32 whereby to maintain, when tightened the movable section 26, immovable relatively to section 25. If desired, a pin 36 may be disposed to extend through bolt 30, the pin 80 maintaining enlargement 27 and the adjacent portion of spring 28 within slot 31 therefor.

When it is desired that a screen of a standard size be laterally increased or diminished in size to provide for its arrangement in window frames varying in measurement, thumb nut 19 is first loosened, thus permitting spring 14 to automatically actuate movable section 11 to its outermost position. This automatic movement of section 11 will provide for use of the screen in windows varying in size, the screen when having been arranged as desired within the window frame being locked or fastened by 95 a tightening of the thumb nut upon the screw.

From the foregoing, taken in connection with the accompanying drawings it is apparent that by so arranging the springs of the attachment, the locking or fastening means may be dispensed with, and the movable section of the screen held in place by the spring tension; that said movable section of the screen is adjustable or movable relatively to the stationary section 6 either against or by tension of the springs associated therewith; and that by forming the respective attachment sections, each from a single strip of metal, the cost of manufacture of the screen attachment is reduced to the minimum without in any way diminishing the operativeness of the device.

In reduction to practice, I have found that the form of my invention, illustrated in the drawings and referred to in the above description, as the preferred embodiment, is the most efficient and practical; yet realizing that the conditions concurrent with the adoption of my device will necessarily vary, 110 I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In an attachment for window screens. 120

5 a fixed section of a construction affording a casing having a marginal slot formed therein, a relatively movable section of a construction providing an enlargement at one end, the enlargement operating within the casing and the movable section operating within the slot, and means engaging the enlarged end of the movable section to maintain said section extended.

10 2. In an attachment for window screens, a fixed section of a construction affording a casing having a slot formed therein, a relatively movable section fitting said slot and of a construction providing an enlargement 75 at one end, spring means engaging the fixed section and the said enlargement to normally maintain the movable section extended, the enlargement operating within the casing and affording a stop means limiting movement of the movable section.

15 3. In an attachment for screens, an attachment section of a construction affording a casing having a slot formed therein, a movable section fitting said slot and partially 80 inclosed within the casing, an enlargement formed upon the inclosed end of said movable section, said enlargement affording a stop means limiting movement of said last mentioned section, spring means engaging 85 the enlargement and the first mentioned section to normally maintain the movable section extended, and means to fasten the movable section against movement.

20 4. In an attachment for screens, a fixed 90 section, a relatively movable section, an enlargement formed upon each of the respective longitudinal edges of said movable section, one of said enlargements being engageable with the fixed section to limit the 95 relative movement aforesaid, means yieldingly maintaining the said enlargement in engagement with the fixed section, and means operating in a slot therefor formed in the fixed section to lock the movable section in its adjusted position.

25 5. In an attachment for screens, a fixed section, a movable section, an enlargement formed upon the movable section and inclosed by the fixed section, the enlargement 100 affording a stop to limit relative movement of the last mentioned section, a spring engaging the fixed section and the enlargement to maintain the movable section extended, and means to releasably lock the movable 105 section in its adjusted position.

30 6. In an attachment for screens, an attaching section comprising a strip of material bent equi-distant from its longitudinal edges to provide a socket within which that edge 110 of the screen to which it is attached is fitted, the adjacent longitudinal edges of the said strip of material being bent inwardly to terminate in parallelism and in spaced relation to provide a marginal slot, a movable section operating within the said slot, and an

115 enlargement formed upon the movable section and inclosed by the fixed section, the enlargement being engageable with the in-turned edges of the fixed section to limit relative movement of the movable section.

7. In an attachment for screens, a fixed section of a construction affording a casing having a slot formed therein, a movable section fitting said slot, an enlargement formed upon said movable section and operating 75 within the casing, a spring engaging the fixed section and the said enlargement to normally maintain the movable section extended, a bracket inclosed by the casing and affixed to the enlargement, and means operating in the 80 slot therefor of the fixed casing to engage the bracket for releasably locking the movable section in its adjusted position.

8. An attachment for window screens including a pair of attachment sections, each 85 of the said sections being formed from a single strip of elongated sheet metal, means fastening one of said sections rigid with the screen, said rigid section being shaped to form a casing within which a portion of the 90 other of the said attachment sections is fitted, means limiting movement of said movable section, and spring means interposed between the said two sections, said spring means normally holding the movable section 95 extended.

9. An attachment for window screens including a pair of attachment sections, one of said sections being formed from a single strip of metal bent to form a casing having 100 a longitudinal slot extending throughout its length, means fastening said section to the screen, the other of the said sections being formed from a single sheet of metal, said sheet of metal being bent to enlarge the said 105 section at each of its respective longitudinal edges, said movable section being adjustable laterally of said immovable section, said movable section operating within the slot aforesaid to dispose one of the said enlargements within the said casing, and spring means interposed between said two sections, the spring means being inclosed within the 110 casing, said means normally holding the movable section extended.

10. An attachment for window screens including a pair of attachment sections, one of the said sections being rigid with the screen, the other of the said sections being movable laterally relatively to the said first mentioned section, spring means interposed between the said two sections normally exerting an outward pressure upon said movable section, and means carried by said movable section operating within a slot formed in 120 said stationary section, said means being actuatable to lock said movable section immovable when adjusted.

11. A window screen attachment including a stationary attachment section, a mov- 125

able attachment section, the said stationary attachment section having a slot formed therein, spring means interposed between said stationary section and said movable section normally exerting an outward pressure upon the latter, and means including a longitudinally slotted bolt engageable with said movable section and extending through the slot in said stationary section for locking said

movable section immovable relatively to the stationary section.

In testimony whereof I affix my signature in presence of two witnesses.

GEORGE WILBUR SHIPLEY.
